UNITED STATES PATENT OFFICE.

FRANCIS W. DUNBAR, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

TELEPHONE TRUNKING SYSTEM.

No. 847,984.

Specification of Letters Patent.

Patented March 19, 1907.

Application filed August 25, 1902. Serial No. 120,878.

To all whom it may concern:

Be it known that I, FRANCIS W. DUNBAR, a citizen of the United States of America, and a resident of Chicago, county of Cook, 5 and State of Illinois, have invented a certain new and useful Improvement in Telephone Trunking Systems, of which the following is a specification.

My invention relates to improvements in 10 telephone trunking systems and apparatus whereby telephone subscribers whose lines terminate at different central offices or central stations may be connected together for conversation.

15 The trunking system of the present invention extends between offices at which subscribers' lines of different types terminate. At the outgoing office the subscribers' lines are provided with cut-off relays and with 20 test-terminals connected in local circuit, and the subscribers' bells are grounded from one side of the line. The operators' cord-circuits are adapted to coöperate with the said lines and are conductively divided but inductively united through the intermediation 25 of a repeating-coil. At an intermediate point of the repeating-coil-winding bridge a supervisory relay is legged to ground through a central battery. With this arrangement 30 of cord-circuits when a connection is established and the subscriber's telephone is upon its hook a path for current from the central battery is provided through the supervisory relay and over the line to the subscriber's 35 station; but when a subscriber's receiver is in use the path for said current is disrupted and the supervisory relay is inoperative. At the incoming office the subscribers' lines are provided with cut-off relays actuated 40 over a portion of the talking-circuits, and the testing-contacts of the jacks are connected directly with one side of the talking-circuits. This trunk-circuit is adapted for use with the said subscribers' lines at the 45 incoming office and with the special type of cord-circuit above described at the outgoing office, the connection being so arranged that the usual method of operation of trunk-circuits is obtained.

50 My invention is shown in the accompanying drawings, in which—

Figure 1 is a diagram of a system of the

kind above described. Fig. 2 is a diagram of a modification in which the repeating-coil at the incoming end of the trunk is replaced 55 by condensers. Fig. 3 is a diagram of still another modification in which condensers are employed and in which the trunk-relay is actuated by current over both sides of the trunk, and Fig. 4 is a diagram of a different 60 form of the invention in which condensers are employed at the incoming end and in which the trunk-relay is actuated by current over the opposite side of the line from that disclosed in Fig. 1. 65

Referring to Fig. 1, L designates one of the plurality of subscribers' lines terminating at the central office C. This line extends in two limbs 2 and 3 from the subscriber's station A to the said central office C, where it is 70 fitted with suitable answering and multiple jacks J and J². At the subscriber's station the usual telephone instruments are provided and consist of a transmitter 4, a receiver 5, a bell 6, and a local battery 7. The 75 switch-hook 8 is adapted in its normal position and when the receiver is placed thereon to open the circuit between the limbs of the line as well as the local circuit of the transmitter and to close the tip-limb 2 through the 80 grounded signaling-bell 6. In its uppermost position a local circuit containing the transmitter 4, local battery 7, and primary of the substation induction-coil is closed, and at the same time the main line is closed through 85 the receiver and secondary of said coil. The cut-off relay R is energized by current from the battery B over a set of conduction including wire 9 to junction-point 10, thence through the cut-off relay R and by the switch-board conductor 11, the auxiliary springs j³ of the jacks, and through the coöperating earth-contacts j⁴. These contacts j³ and j⁴ are closed together when a plug is inserted in a jack and the cut-off relay is actuated. The 95 test-rings j⁵ of the jacks are connected together by means of conductor 12 with the forward contact of spring 13 of the cut-off relay R, the latter being grounded through a resistance-coil 14 of suitable dimensions. 100 The contacts j and j² of the jacks are normally disconnected from the line, but are connected by wires 15 and 16 with the forward contacts of springs 17 and 18 of the cut-

off relay, whereby when the cut-off relay is actuated these contacts are connected with the limbs of the telephone line. The spring 17 of the cut-off relay is normally grounded, 5 while spring 18 is normally connected by means of conductor 19 with the line-signal S, the other terminal of which is joined by conductor 9 with the live pole of battery B, whereby when the subscriber takes up his receiver in calling the central office a complete path for current from said battery is provided over the metallic line and the line-signal S to actuate it, and thereby indicate a call.

15 The cord-circuit is provided with an answering-plug P and with a calling-plug P², each of which has a tip-contact p and a sleeve or stem contact p². These contacts of the answering-plug P are looped together by 20 means of the tip-strand t and sleeve-strand s and the helices o and o² of the repeating-coil O. The plug P² is likewise connected in the loop by the tip-strand t², the sleeve-strand s², and the helices o³ and o⁴ of the said 25 repeating-coil. A supervisory relay r is joined by conductor 20 with the junction-point 21 of the loop of the plug P, and its other terminal is connected by conductors 22 and 23 with the live pole of the battery B. 30 A supervisory lamp S² is included in a circuit with the battery B by means of the armature and forward contact of said supervisory relay r. The opposite plug P² is associated therewith, a supervisory relay r² controlling supervisory signal S³ in a manner similar to the lower parts connected with the other plug of the cord-circuit. The operator's telephone sets comprise the receiver 24, adapted to be bridged across the cord-circuit 35 by the listening-key k k, said bridge including the secondary 25 of her induction-coil and the condenser c. Her transmitter 26, together with the primary 27 of her induction-coil, may be charged from the battery B. 40 The conductors 28 and 29 serve to connect the operator's instruments with the normally open contacts of key k², by means of which she is able to connect her telephone with the order circuit or wire 33, leading to the other 45 exchange. The calling-generator g is adapted to be connected, together with the resistance-lamp 30 between ground and the tip-strand of the calling-plug, by means of the tip-contact of key k³, the sleeve-contact of key k³ serving 50 to ground the corresponding strand to provide a path for the ringing-current in case the subscriber answers during the process of ringing.

A trunk-circuit is shown extending between the central offices C and C², said trunk-circuit being fitted at the outgoing end with jacks J³ and J⁴ and extending to the central office C² in two limbs 35 and 36, where the trunk is provided with suitable means for 60 testing the condition of the wanted line, for

ringing the desired subscriber, and with signals to enable the operator to properly attend the connection. The tip and sleeve trunk conductors 35 and 36 terminate at the incoming office in windings w' and w² of the 70 repeating-coil W, and from a point between said windings a conductor 38 extends to the normal contact of spring 37 of the tip-relay r⁸. The said spring is connected, by means of a conductor 39, with the trunk-relay r⁷, 75 the opposite terminal of which is grounded. The opposite windings w³ and w⁴ of the repeating-coil W, with an interposed condenser c⁵, are connected between the tip-strand t³ and the sleeve-strand s³ of the flexible end of the trunk-circuit. These strands terminate in the corresponding contacts p and p² of the trunk-plug P³. The tip-relay r⁸ is legged to ground from the tip-strand t³ of the trunk-circuit by conductor 36^a. A 80 sleeve-relay r⁹ is connected on one side with the live pole of the battery B³ by means of conductors 40 and 41 and on the other side with the sleeve-strand s³. This incoming end of the trunk is provided with a special testing apparatus. The forward portion of the tip-strand t³ is connected with spring 42 of the sleeve-relay r⁹, while the other portion is connected with the forward contact of said spring. The back contact of spring 42 is 85 joined by conductor 43 with the common high-resistance and high-impedance test-relay r¹⁰, the opposite terminal of which is grounded. The armature of this test-relay serves when actuated to ground one side of 90 the operator's induction-coil 44, which winding is connected on the opposite side with a conductor 45, containing the resistance and impedance coil 46 and joined to conductor 47, which leads directly to the live pole of the 95 battery B³. The operator's transmitter 48 is in a conductor 49, leading from conductor 45 to ground. A condenser c⁶ is connected between conductor 49 and the side of the primary that is adapted to be grounded. The 100 operator's receiver 50 together with the secondary of her induction-coil and the condenser c⁷ are connected permanently with the order-circuit 33, leading to the central office C. The conductor 40 leads to the point 105 54, from which point the branch 55, containing the ringing-lamp S⁴, leads to the back contact of the armature of locking-relay r¹¹, said armature being connected by conductor 55^a to the point 52^a upon the conductor 52 110 extending between the spring 57 of tip-relay r⁸ and the front contact of spring 51 of sleeve-relay r⁹, the latter spring being grounded, as 115 shown. The conductor 56 extends from point 54 to the front contact of spring 57 of tip-relay r⁸ and includes the winding of the locking-out relay r¹¹. The forward contact of the armature of this relay is connected to conductor 56 at point 59^a by means of conductor 58. The back contact of spring 57 of 120

tip-relay r^8 is joined by conductor 59 to the back contact of the armature of trunk-relay r^7 , the forward contact of which is connected by conductor 52^b with the back contact of 5 spring 51 of sleeve-relay r^9 . The armature of the trunk-relay r^7 is connected with a conductor 53, leading to the battery-wire 47 and including the guard and disconnecting lamp S⁵ and the pilot-relay r^{12} , said latter relay 10 serving to control the circuit of pilot-signal S⁶. This incoming end of the trunk is equipped for selectively ringing subscribers upon a party-line. It comprises the ringing-key contacts k^4 k^4 and k^5 k^5 , placed in the 15 strands of the trunk-cord and adapted when actuated to suitably connect the alternating-current generator g^2 with the plug P³. This ringing-generator comprises the armature 60, the grounded brush 61, the brush 62, from 20 which the alternating current is directed through resistance-lamp 63 to tip-key spring k^4 when depressed, and brush 64 from the split commutator-ring, which is adapted to deliver a current of negative pulsations only 25 through lamp 65 to the sleeve-key k^5 when the key is operated. The sleeve contact of key k^4 when operated connects the sleeve of the plug to battery-lead 47 through resistance-coil 66 to maintain the cut-off relay of 30 the line operated during ringing.

The subscriber's line shown in connection with this office is of the "party-line" type and is connected to subscribers D and D². The bell 6 at station D is connected between the 35 sleeve-conductor 3 and ground, while at station D² the bell is connected between the tip-conductor 2 and ground. Normally disconnected jacks J J², line-relay R², cut-off relay R, and the line-signals S are employed. The 40 battery B³ furnishes current for the operation of these various relays and signals, as well as for talking.

In establishing a connection the A subscriber takes up his receiver, and thereby indicates a call through the intermediation of his signal S. The operator in response to this call inserts the answering-plug P of her cord-circuit, thereby actuating the cut-off relay to render the line-signal inoperative and 45 to connect the jack-terminals with the limbs of the telephone-line. The supervisory signal S² remains inert, for the reason that the path for current from the battery B over the telephone-line is at this time open.

50 Upon being informed that a subscriber in the exchange C² is desired the key k^2 is depressed to connect her telephone with the operator's instrument at the said office, who nominates the trunk to be used. Before 55 connecting the trunk-plug with the wanted line the B operator tests the same with the tip of the incoming trunk-plug. If idle, no click will be received; but if the line is busy the sleeve-contacts of the jacks of the line 60 will be connected with the live pole of a bat-

tery similar to the battery B³ through the sleeve-contact and sleeve-strand of the flexible cord of the inserted plug. A complete circuit will therefore be established from the sleeve-contact of the tested jack, which it 70 is assumed is connected with the live pole of a battery through the tip of the plug P³, tip-strand t^3 , spring 42, and back contact of sleeve-relay r^9 , conductor 43, through the common high-resistance and high-impedance 75 test relay or responsive device r^{10} to ground. This test-relay will therefore operate and ground through its armature and front contact one side of the primary of the operator's induction-coil 44, the other side of which is 80 connected by conductor 45 through resistance 46 and conductor 47 to the live pole of the battery B³. The completion of the circuit will permit a flow of current there-through which will induce a current in the 85 secondary of the said induction-coil and produce a click in the receiver 50 of the operator's set. The operator's receiver will respond to this click at all times even though the order-circuit should be open at the 90 exchange, since the electrostatic capacity of her circuits and that of the order-circuit is ample for the purpose of producing the click.

In the three-wire system where the test-circuits are insulated from the subscriber's lines 95 there is no danger of varying the current flowing in the line to the annoyance of the subscriber during testing; but in the two-wire system where the testing-contacts are connected directly with the talking-circuits some means 100 is necessary or at least desirable to prevent noticeably varying the current upon lines connected for conversation when testing their condition at other sections of the switch-board. This is accomplished in the circuit 105 described by means of the test-relay r^{10} , which is of such high resistance as to vary the current upon the tested line but slightly and which is also of high impedance, so that its current will build up slowly to thereby prevent 110 a sudden variation of current on the line. The subscriber or subscribers whose lines are tested are therefore undisturbed by a sudden or large variation of current through their instruments. It is apparent that any 115 other suitable test-responsive device or indicator than the relay r^{10} can be employed and that the operator's telephone can be used in place of the same or in the circuit with a retardation-coil, but the arrangement described 120 is preferred. This relay is preferably common to all the incoming trunks at the one operator's position, as indicated by the branching lines at 43^a. Upon finding the line idle the plug P³ is inserted in one of the 125 multiple jacks of the wanted subscriber's line.

The A operator having received the number of the trunk to be used inserts the calling-plug P² of her cord-circuit in the jack of the 130

trunk at her section. This act completes a circuit from the live pole of the battery B over both sides of the trunk and through the branch 38 at the incoming office, spring 37 of 5 relay r^8 , and conductor 39, through the trunk-relay r^7 to ground. The supervisory relay r^3 is therefore operated and causes the signal S^3 to become visible, thus indicating to the A operator that the called subscriber 10 has not responded.

The insertion of the incoming trunk-plug into the jack of the wanted line closes a circuit from the live pole of the battery B^3 , over conductors 40 and 41, through sleeve-relay r^9 , 15 and thence over the sleeve-strand s^3 of the flexible end of the trunk through the sleeve-contacts of the plug P^3 and the jack of the called subscriber, and thence to the cut-off relay R of the wanted line to ground, thus 20 operating both the sleeve-relay r^9 and the cut-off relay R, the latter serving to disconnect the line-relay R^2 of the line to render the line-signal inoperative and to connect the normally-disconnected jacks with the limbs 25 of the line extending to the substations. The operation of sleeve-relay r^9 disconnects the test-relay r^{10} and closes the tip-strand t^3 through the spring 42 and its forward contact, and thereby establishes the circuit for 30 conversation. It also completes the circuit of the ringing-lamp S^4 from the battery B^3 over conductor 40 to the point 54, thence over conductor 55 and through the lamp S^4 to the back contact of the armature of locking-relay r^{11} , thence through the armature and 35 over conductor 55^a to the point 52^a, over the conductor 52 to the front contact and armature of sleeve-relay r^9 to ground. The completion of this circuit causes the operation of 40 the ringing-lamp S^4 and indicates to the operator that the subscriber has not yet responded. The operation of the trunk-relay r^7 at this time opens through its armature and back contact the circuit of the guard and 45 disconnect lamp S^5 , to thereby prevent its operation.

Upon the insertion of the trunk-plug P^3 the B operator rings the wanted subscriber. If the subscriber D is the one desired, the 50 ringing-key k^5 k^5 is depressed, which throws ringing-current upon the sleeve-strand connected with the plug P^3 and operates the subscriber's bell over the following path: from ground at the generator g^2 , brush 61, armature 60 of the generator, brush 64, through 55 resistance-lamp 65, key k^5 , thence over the sleeve-strand of the cord to the plug P^3 , over the sleeve-limb 3 of the telephone-line to the station D, and thence through condenser 7 and bell 6 to ground, the receiver 5 being at 60 this time upon the hook 8, and therefore completing the circuit between the condenser 7 and bell 6.

It will be noticed that just previous to the 65 depression of the ringing-key k^5 the cut-off

relay R was receiving a negative current through its coils from the battery B^3 . At the instant the ringing-key k^5 is depressed this path of current from the battery B^3 is broken; but a new path is immediately established through the relay R from the negative source of pulsating ringing-current. The relay R is so constructed as to be maintained in continuous operation when this negative pulsating current is passing through 75 its winding, and as pulsations are used of the same direction as the current furnished by the battery B^3 the relay R is prevented from even momentarily releasing its armatures at the moment the ringing-key was depressed. 80

The bell 6 at the subscriber's station may be of the ordinary polarized type, as the presence of the condenser 7, which is connected directly in the ringing-circuit, permits the operation of such a bell from the pulsating 85 source of ringing-current. The tip-spring of ringing-key k^5 is grounded at this time to provide a path to ground for the return-current if the subscriber should respond during ringing. Should the subscriber D² be the one 90 desired, the ringing-key k^4 k^4 is depressed, which serves to connect the generator g^2 with the tip-strand of the cord-circuit to operate the bell at the station D². The ringing-circuit may be traced as follows: from ground 95 at the generator g^2 , brush 61, armature-winding 60 of the generator, brush 62, through resistance-lamp 63, spring k^4 in the tip-strand of the cord-circuit, thence over the tip-strand and tip-conductor 2 of the line to the station D², and thence through condenser 7 and normally closed contacts of the hook 8 and through bell 6 to ground. The bell is thus 100 operated. To maintain the cut-off relay R operated during ringing, the inner contact of the sleeve-spring k^4 is connected, through a resistance-coil 66, with the battery-lead 47, extending to the live pole of the battery B^3 . This prevents the deenergization of cut-off 105 relay R while ringing.

It is apparent that the arrangement of the ringing-keys is such that either key may be used to call a subscriber at whose station the apparatus is connected in the manner shown at A, which shows the arrangement which I 115 preferably use where but one subscriber is placed upon the line. In this case the ringing-circuit would be complete over the subscriber's metallic circuit, the current returning to the grounded side of the ringing-generator by means of the grounded key k^5 or battery-contact of the ringing-key k^4 .

The subscriber having been called responds by taking up his receiver, and thereby closes a path for current between the limbs of his line from the main battery B^3 over conductors 40 and 41, sleeve-strand s^3 of the incoming end of the trunk-line 3 of the telephone-line, thence through retardation-coil 9 and transmitter 4 at the substation, thence over 125 130

limb 2 of the telephone-line back to the central office and over tip-strand t^3 of the incoming end of the trunk, including spring 42 and its forward contact of sleeve-relay r^9 , through 5 conductor 36^a and tip-relay r^8 to ground. This relay responds to this current and opens through its spring 37 and back contact a circuit of the trunk-relay r^7 , which causes the deenergization of the supervisory relay r^2 in 10 the A cord-circuit and the consequent retirement of the supervisory signal S^3 , thus indicating to the A operator that the called subscriber has responded. Although the trunk-relay r^7 is now deenergized and its armature 15 engages its back contact, the guard-lamp S^5 is not operated, because its circuit is opened at the back contact and spring 57 of tip-relay r^8 . The closing of spring 57 of the tip-relay r^8 and its forward contact completes the circuit of the locking-relay r^{11} , as follows: from 20 the live pole of the battery B^3 over conductor 40 to the point 54, thence through the locking-relay r^{11} , over conductor 56 to the forward contact and spring 57 of the relay r^8 , 25 thence over conductor 52 through the forward contact and spring 51 of sleeve-relay r^9 to ground. The locking-relay r^{11} is therefore operated and opens through its armature and back contact the circuit of the ringing-lamp S^4 , which is extinguished and indicates 30 to the operator that the called subscriber has responded to his ring. The closing of the armature of the locking-relay upon its forward contact completes a locking-circuit for said 35 relay from the point 59^a through conductor 58, the forward contact and the armature of the relay, conductor 55^a to point 52^a, and thence over conductor 52 and the forward contact and spring 51 of sleeve-relay r^9 to 40 ground. This circuit and the relay r^{11} are therefore locked, and the ringing-lamp S^4 is also locked out during the remainder of the connection and can only be released when the sleeve-relay r^9 is deenergized, which occurs when the plug P is pulled out.

Should the tip and sleeve contacts of the plug be crossed when the plug is inserted in a jack and the locking and other relays operated, they will be immediately released by 50 the opening of the sleeve-strand in ringing, and no confusion would result therefrom. The subscribers are now connected together for conversation, and the supervisory signals at both exchanges are extinguished.

55 During conversation the local battery at the substation is furnishing current to the transmitter for conversation, the voice-currents being conducted over the metallic line and propagated in the trunk-line through the 60 medium of the repeating-coil in the A-cord circuit, and from the trunk-line they are repeated by means of the coil W , into the called line. The battery B^3 at the B office furnishes current over the trunk-cord and 65 the subscriber's line L^2 to the substation upon

said line for the operation of the transmitter. Thus at one exchange the subscribers are provided with local-battery transmission and at the other with common-battery transmission.

At the termination of the conversation the subscribers return the receivers to their hooks, with the result in the case of subscriber A that the supervisory relay R is operated by current over one side of the line and through the grounded signaling-bell at 70 the substation. The supervisory signal S^2 is therefore actuated. When the subscriber D hangs up his telephone, current is cut off from the metallic line and the tip-relay r^8 is deenergized, thus closing circuit from the 75 battery B in the A-cord circuit over the trunk-line and permitting the actuation of the supervisory relay r^2 and the supervisory signal S^3 . This indicates to the A operator that the called subscriber has replaced his telephone upon its hook. The spring 57 of the tip-relay r^8 at the incoming end of the trunk is now closed to conductor 59; but the trunk-relay r^7 , having operated the circuit of the disconnecting-lamp S^5 , is again opened. 80 The A operator seeing both signals in her cord-circuit exposed withdraws both plugs, thus restoring all parts at her office to normal position. The withdrawal of the plug P^2 at the A exchange deprives the relay r^7 at 85 the incoming end of the trunk of operating-current, which is therefore deenergized and permits its armature to close upon its back contact the circuit of the disconnecting-lamp S^5 and the pilot-relay r^{12} , said circuit being 90 traced from the live pole of the battery B^3 to conductor 47 through the winding of the pilot-relay r^2 and through lamp S^5 , thence over conductor 53, the armature and back contact of trunk-relay r^7 , conductor 59, the back contact 95 and armature 57 of tip-relay r^8 , thence over conductor 52 to the front contact and armature 51 of the sleeve-relay r^9 to ground. The operation of the pilot-relay r^{12} lights the pilot-signal S^6 , which attracts the operator's attention and who upon observing the lighted lamp S^5 is thus informed that the A operator 100 has taken down the connection at that exchange, and she accordingly withdraws the plug P^3 from the jack of the subscriber's line. 105 Upon the withdrawal of the trunk-plug the sleeve-relay r^9 is deenergized and the circuit of the signal-lamp S^5 , as well as that of the pilot-relay r^{12} , opened at the front contact 110 and armature 51 of the said relay. Both 115 lights S^5 and S^6 are thus extinguished, and at the same time the circuit of the locking-relay r^{11} is broken at the same point, which relay is therefore deenergized and permits its armature to return to normal position. The dis- 120 connecting-signal S^5 serves also as a guard-lamp in case the A operator inserts the calling-plug P^2 into wrong trunk-jack, for the 125 reason that the trunk-relay of that trunk will be operated, while the sleeve-relay r^9 is 130

not operated. A circuit will therefore be completed from the live pole of the battery B³ over conductor 47, through pilot-relay r¹² and disconnecting-lamp S⁵, through conductor 53, the armature and front contact of trunk-relay r⁷, conductor 52^b to the back contact of sleeve-relay r⁹, thence through the armature 51 to ground. The disconnecting-lamp S⁵, as well as the pilot-lamp S⁶, will therefore be lighted and will indicate to the operator that a mistake has been made. At the same time both ringing-lamp S⁴ and guard-lamp S⁵ of the trunk whose plug is inserted will operate, thus assuring the operator that the trunk has not been connected with at its opposite end. It will be noticed that the sleeve-relay spring 51 controls through its forward contact a ground branch from point 52^a and that from said point two parallel paths are normally completed to the live pole of the battery, one including conductor 55^a, the normal contacts of locking-relay r¹¹, ringing-lamp S⁴, conductors 55 and 40, while the other includes conductor 52, the normal contacts of tip-relay r⁸, conductor 59, the normal contacts of trunk-relay r⁷, conductor 47 to the battery. When ground is thrown upon these parallel paths, as by the closing of the sleeve-relay r⁹, both lamps are operated. This can only occur under these circumstances, for the reason that in normal working before the subscriber responds both the trunk-relay and the sleeve-relay are operated, the former serving to open one parallel path, which permits only the ringing-lamp to operate.

As soon as the subscriber responds the locking-relay operates and holds open the parallel path through its contact during the remainder of the connection. At the same time, although the trunk-relay is no longer operated, the tip-relay is operated, which again opens the first path, so that lamp S⁵ cannot glow. Now when the A operator takes down the connection lamp S⁵ operates; but the other parallel path remains open through locking-relay r¹¹.

The order-circuit 33, as is indicated by the branch in lines 33^a, connects the B operator with several A operators either at the same or different exchanges. The A operator is also provided with a plurality of keys k² to connect herself with the different B operators.

Although I have described the method of making connections through the medium of the order-circuit, I do not wish to so confine the invention, for it is apparent that the A operator is able by means of her testing apparatus to test the condition of the several trunks before her until an idle trunk is found, this being accomplished in any well-known manner and by any well-known apparatus, such as is shown in connection with jacks of line L. Upon so testing and finding an idle trunk she may insert the calling-plug P²

of her cord-circuit, with the result that the trunk-relay r⁷ operates and lights the lamp S⁵, which lamp has been previously termed the "guard-lamp," but in this method of operation it would act as a calling-signal from the A operator to the B operator. The B operator upon seeing the signal S⁵ would depress her listening-key k⁶ k⁶, which would connect her receiver in series with the repeating-coil windings w³ and w¹, these receiver connections being indicated in dotted lines in Fig. 1. She is therefore able to communicate with the A operator. Upon learning the desired connection the B operator completes the same, as before described. It will also be understood that had the subscriber A called for a connection with another subscriber in the same exchange the line of that subscriber would have been tested in the ordinary manner by means of the cord-plug P², and the subscriber would have been called by the ringing-generator g.

Fig. 2 shows a modification in that the repeating-coil W at the incoming end of the trunk is replaced by condensers c¹⁰ and c¹¹, and the trunk-relay r⁷ is actuated over the tip side only of the trunk, the connections otherwise being the same as in Fig. 1. It is apparent that the parts will operate in the same way and the same results will be accomplished as in the case of Fig. 1. It is therefore deemed unnecessary to describe the operation or parts in detail.

Fig. 3 represents the circuit in which condensers c¹⁰ and c¹¹ are employed in place of the repeating-coil windings and in which the trunk-relay r⁷ is actuated by current over both sides of the trunk and ground instead of merely over the tip side of the trunk and ground, as shown in Fig. 2. Otherwise the construction and arrangement is the same as in the said Fig. 2, and the operation is the same as in both Figs. 1 and 2 and does not need further description.

Fig. 4 shows the condensers employed as in the two preceding figures; but the trunk-relay is actuated by current over the sleeve side of the trunk instead of over the tip side, as in Fig. 2. The complete operation of this system also will be understood from what has been said in reference to Fig. 1.

The ground connections heretofore referred to, it will be understood, may and in practice usually are one and the same, or they may be the common office return, although it is found in practice that it is necessary to place a dead ground upon one side of the common battery. These ground connections may be placed at the opposite pole of the several batteries instead of as shown in the diagram, all of which is apparent to those skilled in the art. The pilot-relay may have one and one-half ohms resistance and the other parts may be of the desired or usual dimensions.

Having thus described my invention, what I claim, and desire to secure by Letters Patent, is—

1. The combination with a trunk-circuit extending between different switchboard-sections and adapted to connect subscribers' lines together for conversation, of a trunk-relay at the incoming end legged to ground from the outgoing end of the trunk and actuated by current thereover when connection exists at the outgoing end, a second relay at the incoming end of the trunk actuated by current over a portion of the talking-circuit when connection is established with the called line, and a signal at the incoming end whose actuation depends upon said relays, and means for disconnecting said trunk-relay from the outgoing end of the trunk when the called subscriber answers, substantially as described.
2. The combination with a trunk-circuit extending between different switchboard-sections and adapted to connect subscribers' lines together for conversation, of a relay at the incoming end of the trunk connected to ground from the outgoing end and actuated by current over the trunk when connection exists at the outgoing end but adapted to be disconnected therefrom when the called subscriber answers, a second relay at the incoming end actuated by current over a portion of the talking-circuit when connection is established with the called line, and a signal whose actuation depends upon said two relays, said signal being actuated when the connection exists at the outgoing end only to give a guard indication, and to act as a disconnect-signal when the called subscriber has hung up his receiver and connection has been severed at the outgoing end, substantially as described.
3. The combination with a trunk-circuit extending between different switchboard-sections and adapted to connect subscribers' lines together for conversation, of a disconnect-signal at the incoming end of the trunk placed in condition to operate by current over a portion of the talking-circuit when connection is established with the called line, and a trunk-relay connected between the outgoing end of the trunk and ground and actuated by current over the trunk when a connection exists at the outgoing end, said relay serving when actuated to prevent the operation of said signal, and means to disconnect said relay from the outgoing end when the called subscriber responds, substantially as described.
4. The combination with a trunk-circuit extending between different switchboard-sections and adapted to connect subscribers' lines together for conversation, of a disconnect-signal at the incoming end placed in condition to operate by current over a portion of the talking-circuit when connection

is established with a called line, a trunk-relay adapted when energized to prevent the operation of said signal, said relay being actuated by current over both sides of the trunk with suitable return when connection is established at the outgoing end, and means for disconnecting said relay when the called subscriber responds, substantially as described.

5. The combination with a trunk-circuit extending between different switchboard-sections and adapted to connect subscribers' lines together for conversation, of a disconnect-signal for the incoming end of the trunk, a relay actuated over a portion of the talking-circuit when connection is established with a called line to place said signal in condition to operate, a trunk-relay adapted when actuated to prevent the operation of said signal, said relay being connected at the incoming office between the outgoing end of the trunk and ground, a source of current likewise connected at the outgoing office when the connection is established at said end, a third relay responsive to current in the line when the called subscriber answers to sever the connection of said trunk-relay with the circuit, said third relay being arranged to prevent the operation of said signal while the trunk-relay is disconnected, substantially as described.

6. The combination with a trunk-circuit extending between different switchboard-sections and adapted to connect telephone-lines together for conversation, of a disconnect-signal for the incoming end of the trunk, a relay placed in condition to operate by current over a portion of the talking-circuit when connection is established with the called line, a trunk-relay with its coil permanently connected to ground and adapted to be actuated over the two limbs of the outgoing end of the trunk in parallel and ground, when a connection is established at the outgoing end, said relay serving to prevent the operation of said signal, and a pilot-relay at the incoming end actuated simultaneously with said signal, substantially as described.

7. The combination with a trunk-circuit extending between different switchboard-sections and adapted to connect telephone-lines together for conversation, of a guard-signal at the incoming end, a trunk-relay actuated over both sides of the circuit of the outgoing end of the trunk and ground when the connection exists at said outgoing end, said relay serving to place said signal in condition to operate, and a second relay actuated by current over a portion of the talking-circuit when a connection is established with the called line to render said signal inoperative, substantially as described.

8. The combination with a trunk-circuit extending between different switchboard-sections and adapted to connect telephone-lines

together for conversation, of a guard-signal for the incoming end of the trunk, a trunk-relay connected between both the outgoing ends of the trunk and ground and actuated 5 by current thereover when a connection exists therewith at the outgoing end to place said signal in condition to operate, a second relay at the incoming end actuated by current over a portion of the talking-circuit when connection is established with the called line and 10 normally completing the circuit of said signal, and a pilot-signal at the incoming end actuated simultaneously with said guard-signal, substantially as described.

15 9. The combination with a trunk-circuit extending between different switchboard-sections and adapted to connect telephone-lines together for conversation, of a cord-circuit at the outgoing end to connect with said trunk, 20 a repeating-coil having its windings connected across said cord-circuit, a relay legged from the middle point of the windings connected with the trunk end of the cord-circuit to the live pole of a battery, a signal controlled by said relay, a trunk-relay at the incoming end of the trunk legged to ground from the outgoing end, and means to sever the connection of said trunk-relay with the trunk when the called subscriber responds, 25 whereby both the trunk-relay and the supervisory relay at the outgoing end are rendered inoperative, substantially as described.

10. The combination with a trunk-circuit extending between different switchboard-sections and adapted to connect telephone-lines together for conversation, of a disconnect-signal at the incoming end of the trunk, a source of current at said end, a relay also at said end to place said signal in condition to 30 operate and actuated by current from said source over a portion of the talking-circuit when connection is made with the called line, a trunk-relay at the incoming end connected between the outgoing end of the trunk and 35 ground and actuated by current sent over the trunk from the outgoing end when connection is established at said end, said trunk-relay serving to prevent the operation of said signal when energized, a third relay at the 40 incoming end responsive to current in the line when the called subscriber answers, said

relay serving to disconnect the trunk-relay and to prevent the actuation of said signal when energized, said current source serving to charge the transmitters for talking as well 55 as for the operation of some of said relays, substantially as described.

11. The combination with a trunk-line extending between different switchboard-sections, of a cord-circuit adapted to be connected with said trunk at its outgoing end, and a called subscriber's line with which its incoming end is adapted to be connected, a supervisory relay associated with the cord-circuit and a trunk-relay associated with the incoming 60 end of the trunk-line, said relays being adapted to be actuated simultaneously by current over the outgoing end of the trunk, ground, and through their windings in series when connection is established at the outgoing 65 end of the trunk, of signals associated, one with each of said relays and adapted to be displayed by the actuation thereof, a second relay associated with the incoming end of the trunk actuated when connection is established with the called line to render one of 70 said signals inoperative and a third relay associated with the same end of the trunk actuated when the called subscriber responds to render the other of said signals inoperative, 75 substantially as described.

12. The combination with a trunk-line extending between different switchboard-sections, of a cord-circuit adapted to be connected with said trunk at its outgoing end, 80 and a called subscriber's line with which said trunk is adapted to connect at its incoming end, of a supervisory relay associated with the cord-circuit, and a trunk-relay associated with the incoming end of the trunk-line, said 85 relays being in series with the two limbs of the trunk-line in parallel, and having their circuit controlled by the position of the called subscriber's receiver-hook, substantially as described. 90

Signed by me at Chicago, county of Cook, State of Illinois, this 29th day of July, 1902.

FRANCIS W. DUNBAR.
